(57) **CLAIM**

The ornamental design for a diffuser panel face plate, as shown and described.

DESCRIPTION

FIG. 1 is a perspective front view of a diffuser panel face plate;

FIG. 2 is a front elevation view of a diffuser panel face plate; FIG. 3 is a rear elevation view of a diffuser panel face plate; FIG. 4 is a left side elevation view of a diffuser panel face plate; the right side elevation view being a mirror image thereof;

FIG. 5 is a top plan view of a diffuser panel face plate; the bottom plan view being a mirror image thereof; and,

FIG. 6 is a perspective front view of the diffuser panel face plate laid out with additional diffuser panel face plates together; size has been scaled down to fit on page.

The additional diffuser panel face plates shown in broken lines depict environmental subject matter only and form no part of the claimed design.
